UNITED STATES PATENT OFFICE

2,000,473

GRATE

John F. O'Connor, Chicago, Ill.

Application February 10, 1933, Serial No. 656,076

6 Claims. (Cl. 126—180)

This invention relates to improvements in grates and more particularly grates or fuel supporting means for furnaces such as those used in generating steam and usually operated at a high rate as for instance, locomotives, marine boilers and the like.

One object of the invention is to provide a grate or fuel supporting means such that the fuel supporting areas are finely divided and with intervening air vents so as to prevent loss of fuel by accidental passage thereof through the grate to the ashpan before completion of combustion and to obtain better air distribution to the bed of fuel, more uniform and efficient combustion thereof and higher firebox temperatures, than heretofore.

Another object of the invention is to provide a grate or fuel supporting means of the character above indicated wherein the fuel supporting units proper and, optionally, the carrier bars therefor, are so constructed as to combine the functions of radiating the heat from the adjacent fuel with sufficient rapidity to prevent excessive heating or burning of the supporting units and, simultaneously, utilizing said radiated heat for preheating the air for combustion effectively and rapidly as the air is passed to and into the fuel bed.

Other objects of the invention are to provide a grate of the character indicated wherein are employed rockable carrier bars on which are detachably assembled the fuel supporting units proper; to provide fuel supporting units such that the supporting surfaces proper thereof present no sharp or fine points projecting into the fuel to thereby minimize possibility of the units being burned out wholly or in part; to provide fuel supporting units of such character that the same may be manufactured in mass quantities at relatively small expense and, further, so designed as to necessitate a minimum weight or quantity of material.

Other objects of the invention will more clearly appear from the description and claims hereinafter following.

In the drawings forming a part of this specification, Figure 1 is a part sectional view, part side elevational view of a grate or fuel supporting means embodying one form of the invention, parts being broken away in order to accommodate the figure on the sheet. Figure 2 is a vertical transverse sectional view corresponding to the section line 2—2 of Figure 1. Figure 3 is a longitudinal vertical sectional view corresponding to the section line 3—3 of Figure 2. Figure 4

is a vertical, transverse sectional view corresponding to the line 4—4 of Figure 3. Figure 5 is an end elevational view of a carrier bar and fuel supporting units proper assembled therewith embodying another form of the invention. Figure 6 is a partial, sectional view, part elevational view of the structure shown in Figure 5 and corresponding to the line 6—6 thereof. Figure 7 is a vertical, sectional view, corresponding to the line 7—7 of Figure 6. Figure 8 is a view similar to Figure 5 but showing the carrier bar in section embodying another form of the invention, the section corresponding to the line 8—8 of Figure 9. Figure 9 is a longitudinal sectional view corresponding to the line 9—9 of Figure 8. And Figure 10 is an end elevational view of the trunnion adapter employed in the construction shown in Figure 8.

Referring first to the form shown in Figures 1 to 4, 10 indicates one of the side supporting frames or plates of the furnace construction such as commonly found, for instance, in locomotives, the same being provided with a plurality of trunnion lugs 11 projecting inwardly and the number of which corresponds to the number of grate bars to be used. Said lugs are preferably of truncated conical form, as clearly shown in the drawings.

Rockably mounted on each aligned pair of trunnions 11 is a carrier bar designated generally by the reference character A. Said bar A, in transverse section, is of approximately heavy or thick, inverted U-form with depending side arms 12—12 and an upper curved uniting section 13, as best shown in Figure 2. With this construction, a longitudinally extending vertical recess 14 is formed in the bar with the same opening downwardly as will be apparent. Each of the side arms 12, is shown provided with a plurality of transversely extending and aligned openings or vents 15—15 to permit of air circulating therethrough, each of said openings 15 preferably being vertically elongated and outwardly tapered from the center line of the bar to the exterior thereof. Also, the upper curved section 13 of the bar is provided with a longitudinal series of openings or vents 16—16, each longitudinally elongated and preferably upwardly tapered as shown. As will be evident, all of the openings or vents 15 and 16 communicate with the recess 14 so that air entering the recess 14 passes upwardly and thence part of the same laterally and the balance upwardly through the slots or openings 16, thus providing for a diffused circulation of the air and preheating thereof in

its passage into and through the carried bar. At each end, the bar A is formed with a semi-circular trunnion bearing 17 conformed to the trunnions 11, as best shown in Figure 3 so that the carrier bar may be easily dropped into place and easily removed when desired and, at the same time, allow for the necessary rocking. The upper section 13 of the bar A is gradually thickened from each end toward the middle, as best shown in Figure 3, so as to provide the necessary beam strength, as will be understood. Each carrier bar A is adapted to be rocked by means of a lever member B which is assembled endwise thereover and disposed centrally of the bar. Said member B is apertured to correspond with the outside contour of the bar A and is provided with an upwardly projecting wedge shaped lug 18 which fits within the recess 14, whereby a detachable but non-rotative connection is made between the member B and bar A for effecting rocking of the latter when the member B is rocked. The latter has a downwardly curved arm 19 apertured as indicated at 201, to provide for suitable connection to the usual linkage to effect rocking. To merely shake the fuel bed, the arm 19 is moved counterclockwise, preferably through an arc of approximately 15° and is moved clockwise to dump the fuel bed, this movement being preferably approximately 60°. Detachably mounted or assembled on each carrier bar A, is a plurality of fuel supporting units each designated generally by the reference character C. Each of said units C comprises a vertically extending and relatively thin web 19 so arranged as to extend transversely of the bar A when in assembled position. Along the top edge of the web 19, which is of arcuate contour when the unit is viewed in elevation as shown in Figure 2, are two series of lugs or fingers 20—20, one series extending to one side of the web and the other series to the opposite side. The lugs or fingers 20 are of relatively small cross section; are laterally spaced; and taper from the web to their outer ends, whereby a series of small openings, vents or passages 21—21 are provided, which are tapered upwardly between each adjacent pair of fingers, as clearly shown in Figure 2. The upper surfaces of the fingers or lugs 20 are also preferably curved or convex as the units C are viewed in section as shown in Figure 3.

The web 19 of each unit C is centrally apertured as indicated at 22 to correspond to the exterior contour of the bar A so that the units may be slipped or threaded endwise over the bar into proper position. Immediately adjacent the opening 22, a shallow rib is formed therearound on each side of the web, as indicated at 23, to provide suitable reinforcement. On each side of the web 19 and at each side of the central aperture 22 below and entirely separate from the fingers 20, are provided series of integrally formed flanges 24—24, the latter being spaced and each extending from the upwardly and outwardly inclined outer edges 25 of the web, upwardly and inwardly, said flanges being progressively shorter from top to bottom of each series and all terminating below the fingers 20. The flanges 24 are preferably tapered in cross section, as shown in Figure 2, and are of such width that the outer edges 27 thereof will preferably come into contact with those of the next adjacent unit when the parts are assembled and, at the same time, leave a narrow opening 28 or clearance between the adjacent opposed

ends of the fingers 20, as shown in Figure 3.

With the construction of the unit C as described, it will be seen that a relatively large number of curved, finely divided or separated supporting areas for the fuel are provided and without any sharp points or the like projecting into the fuel bed, thus minimizing possibility of burning off any portions of the units. Furthermore, heat from the fuel bed will be conducted downwardly through the web and from the latter to the flanges 24 which provide upwardly and inwardly inclined passages 29 converging or directed in a general direction toward the central top area of the unit for the air of combustion so that a large metal area is presented not only for conducting the heat away from the fuel supporting surfaces proper but for also simultaneously transferring such heat to the upwardly flowing air for combustion. The arrangement of the air passages is also such as to accelerate the velocity of the air in its movement through the passages or flues and this air is delivered to the fuel supporting surfaces in finely divided streams over the entire area. These functions are performed not only by the units C but also in part by the carrier bar A, as previously described. With this construction, the delivery of air in a preheated condition to the fuel through the relatively small or fine openings is rendered uniform and steady, thus insuring efficient combustion and minimization of clinkering and at the same time preserving the life of the units C. To hold the units C in assembled position on the carrier bar, the latter at each end has its depending arms 12 slightly undercut, as indicated at 30—30 in Figure 4, and a U or horse-shoe shaped, preferably wrought iron plate 31 is dropped over the bar and drawn together so as to engage beneath the shoulders formed by the recess 30. By spreading apart the depending arms of the plates 31, the latter can obviously be readily removed and the units C then taken off of the bar, as will be understood.

Referring next to the construction shown in Figures 5, 6, and 7, 110 indicates the side frames 45 of the furnace construction, 111 the trunnion lugs; A' the carrier bar; and C' the supporting units.

In this construction, the bar A' is preferably formed with a centrally extending web 43 of 50 gradually increasing depth from its ends to the middle and is also transversely apertured at intervals as indicated at 41—41. At each end, it is provided with an arcuate flange 42 adapted to fit over the trunnion lugs 111, as will be understood. The bar A' is further provided, along the top thereof, with alternated projections 43 and depressions 44 spaced according to the size of the units C'. Also, along each side of the web 40, the bar A' is provided with an upper 60 longitudinally and horizontally extending rib 45 tapered outwardly in section; an intermediate horizontally and longitudinally extending rib 46 having a flat top surface but undulating underneath surface, as indicated at 47, and likewise 65 tapered in section; and a lower generally horizontally extending but undulating rib 48, likewise tapered in section. The intermediate rib 46 is notched or recessed along its outer edge at intervals as indicated at 49, the latter being 70 aligned with the top projections 43 for the purpose hereinafter described. The bottom rib 48 is also notched at intervals as indicated at 48, the latter being opposite the depressions 44 and longitudinally offset from the notches 49. 75

Each of the units C' comprises a central vertical web 119; top series of laterally extending, spaced, tapered fingers 120; and a plurality of upwardly and inwardly inclined, substantially parallel radiating and flue-forming flanges 124, all functioning substantially the same as the corresponding parts of the units shown in Figures 1 to 3 and heretofore described. The web 119 is provided with a downwardly opening centrally disposed recess 122, which is widened at its lower portion as indicated at 222, the latter portion being reinforced by narrow flanges 223. The portion of the opening 222 is of such width that the same may be readily passed over all three of the ribs 45—46 and 48 and the upper portion of the opening 122 is of such width as to pass over the upper rib 45 only. Near the lower ends of the side walls defining the portion 222 of the opening, each unit C' is provided with opposed inwardly extending conical lugs 49 so spaced that they may be dropped through the notches 146 of the intermediate ribs and, when the unit is shifted lengthwise of the carrier bar, then dropped into the notches 148 of the lower ribs, as shown in Figure 7. With this construction, it will be observed that the units C', after they have been assembled with the carrier bar, cannot accidentally be vertically removed or displaced but must either be shifted endwise of the bar opposite the notches 146 or partially shifted and tilted so as to permit withdrawal of the lugs 49 through the notches 146.

At each end of the carrier bar is applied a retainer 50 substantially similar in all respects to a unit C' except that it is somewhat narrower and, at the bottom of the central opening thereof, is provided with inturned lugs 150—150, which engage beneath the lower ends of the U-shaped flange 142.

In the construction of Figures 5, 6 and 7, it will be observed that small or finely divided areas are provided for supporting the fuel; the air for combustion is preheated as it flows and is directed to the fuel supporting surfaces substantially as in the case of the structure previously described and shown in Figures 1 to 4.

Referring next to the construction shown in Figures 8, 9 and 10, the carrier bar A² is there shown of non-circular and preferably square cross section throughout its length except at its ends where it is turned down into a cylindrical trunnion, as indicated at 60. Secured to each end of the bar A² is a trunnion adapter 61, which preferably comprises a cylindrical sleeve section 62 riveted to the trunnion section 60, as indicated at 63, and a flange section 64 recessed as indicated at 65 to receive the square end of the bar therewithin for a short distance. In this form of the invention, the grate bar is shown adapted to rock in a bearing 66 formed by a flange integral with the side frame 210. As will be understood by those skilled in the art, anyone of the constructions shown may be adapted or modified so as to operate either with trunnion lugs, such as shown at 11 and 111, or with a bearing as shown at 66 in Figure 9, all without departing from the spirit of the invention.

Each of the fuel supporting units C² of the Figures 8 and 9 construction, also embodies a web 219 extending transversely of the carrier bar and a plurality of integrally formed radiating and passage-forming flanges 224 extending from the edges of the web diagonally or in an inclined direction upwardly and toward the cen-

ter line of the unit, as clearly shown in Figure 8. Preferably also, the web of each unit C² is provided with a plurality of openings or perforations 67 to lessen the amount of material required and also to increase the radiating functions of the unit. Along the top edge of the web which is of arcuate contour as in the previously described forms, is provided a plurality of fuel supporting fingers 220—220 extending to both sides of the web and likewise of curved or convex contour in section as best shown in Figure 9. In the formation of the fingers 220, the latter are separated by transversely extending grooves or corrugations 68—68 which extend not only over the top areas but also down the sides of the fingers as shown in Figure 9, thereby providing the necessary air passages or spaces for the incoming preheated air to the fuel.

The web of each unit C² is centrally apertured with a non-circular opening 69 conforming to the non-circular cross section of the carrier bar so that the units may be assembled endwise over the bar and provide therewith a relatively rigid or non-rotative connection. Preferably, the webs are reinforced around the openings 69 by shallow ribs 70—70.

Due to variations occurring in lengths of carrier bars and the desirability of making up the units C—C'—C² of one standard pattern or size, it is sometimes desirable to vary the spacing of the fuel supporting units on a carrier bar so as to insure a complete supporting area for the fuel without excessive gaps or spacings between the units which might otherwise permit the fuel to drop through to the ashpan. In such cases where the variation does not permit of the addition of another unit C², one or more spacers may be employed as indicated at 71, each of the same comprising preferably a plate of the general contour of the unit and centrally apertured to allow the same to be slipped over or threaded onto the carrier bar, as shown in Figure 9. When in place, the spacers 71 will contact with the edges of the flanges 224 and in conjunction with the latter provide the flues or passages for directing the air for combustion upwardly to the fuel, as will be understood.

All of the fuel supporting units shown and described will preferably be made from gray iron in the form of castings. It will also be noted that the same are of such design that they may be cast in quantity on gated patterns, no cores, chills, chaplets or the like being required. The patterns of the castings are also such that the molding may be done on a vibrator plate machine, thus reducing the cost to a minimum. The carrier bars of the forms shown in Figures 1 to 7 inclusive will preferably be made in the form of steel castings and the carrier bar A² preferably made from rolled steel. As will be apparent from the preceding description, the fuel supporting units may readily be replaced in the event of injury to anyone thereof.

Although the constructions herein shown and described are now considered the preferred manner of carrying out the invention, nevertheless various changes and modifications may be made without departing from the spirit of the invention and all such changes and modifications are contemplated that come within the scope of the claims appended hereto.

What is claimed is:

1. A fuel supporting unit for a grate and adapted to be detachably mounted on a carrier

bar, said unit comprising: a vertical web arranged to extend transversely of the carrier bar; a series of fingers along the top of the web extending transversely of the latter and to opposite sides thereof; and a plurality of heat radiating flanges on the sides of the web, said flanges extending from the side edges of the web inwardly and upwardly and terminating below the fingers and defining air preheating passages for the air of combustion.

2. A fuel supporting unit for a grate and adapted to be detachably mounted on a carrier bar, said unit comprising: a vertical web arranged to extend transversely of the carrier bar; a series of fingers along the top of the web, extending transversely of the latter and projecting to both sides thereof to provide a vented supporting surface; and a plurality of spaced heat radiating flanges on the sides of the web, said flanges defining passages for and serving to preheat the currents of air passing to the vented supporting surface, the over-all width of said flanges being slightly greater than the over-all width of said top fingers, the flanges of adjacent units being adapted to contact when the units are assembled on a carrier bar.

3. A fuel supporting unit for a grate and adapted to be detachably mounted on a carrier bar, said unit comprising: a vertical web arranged to extend transversely of the bar when assembled thereon; a plurality of spaced fingers on each side of the web along the top edge thereof; and a plurality of inwardly and upwardly inclined flanges on each side of the web and on opposite sides of the center line thereof.

4. A fuel supporting unit for a grate and adapted to be detachably mounted on a carrier bar, said unit comprising: a vertical web arranged to extend transversely of the carrier bar when assembled thereon, said web being provided with a non-circular opening therein for the reception of the carrier bar; spaced finger-like fuel-supporting portions along the top edge of the web; and means formed integrally with

the web to provide passages for preheating the air of combustion, said means being so located and formed that said passages converge upwardly from the side edges of the web and toward the center of the top of the unit.

5. A fuel supporting unit for a grate and adapted to be detachably mounted on a carrier bar with a plurality of like adjacent units, said unit comprising: a vertical web arranged to extend transversely of the carrier bar when assembled thereon and having an arcuate upper edge contour; a plurality of fuel-supporting fingers extending from each side of the web along the top edge thereof, said fingers being also of arcuate contour in a direction transversely of the web and providing substantially smooth, spaced, curved supporting surfaces; and a plurality of flanges on each side of the vertical center line of each side, the flanges on each side of the web being inclined upwardly from the side edges of the web and in a general direction toward the vertical center line of the web, said flanges being separate from and all disposed below the fingers.

6. A fuel supporting unit for a grate adapted to be detachably mounted, with like units, on a carrier bar, said unit comprising:—a vertical web arranged to extend transversely of the carrier bar when assembled thereon, said web being provided with a centrally disposed opening therein for the reception of the carrier bar; spaced, finger-like fuel-supporting portions along the top of the web; and means formed integrally with the web, at each side of said opening, to provide passages for preheating the air of combustion, said means at each side being so constructed that the passages formed thereby extend in an upward direction and toward the vertical center line of the web whereby delivery of air about the finger-like fuel-supporting portions in the area above the carrier bar, is insured.

JOHN F. O'CONNOR.
